UNITED STATES PATENT OFFICE.

JÖRGEN BJÖRNSTAD, OF CHARLTON, ENGLAND.

STEAM-SUPERHEATER.

SPECIFICATION forming part of Letters Patent No. 769,297, dated September 6, 1904.

Application filed March 22, 1904. Serial No. 199,410. (No model.)

To all whom it may concern:

Be it known that I, JÖRGEN BJÖRNSTAD, engineer, a subject of the King of Sweden and Norway, residing at River View, Victoria 5 Road, Charlton, in the county of Kent, England, have invented certain new and useful Improvements in Steam-Superheaters, of which the following is a specification.

My invention relates to the class of apparatus wherein tubes arranged like what are known as "Field" tubes are employed, these tubes being immersed in the hot gases or cooling medium, by which vapors or gases passing through the said tubes are heated or 10 cooled, and the apparatus in accordance with my invention is more especially designed for use in the flues of steam-boilers for superheating the steam generated in the boilers, and has for its object to provide a simple and readily- 15 constructed apparatus in which the steam is very equally distributed, so as to be caused to pass practically equally into all of the tubes of the apparatus; but my invention is not limited to that use, as it can be used generally 20 for effecting interchange of temperature between fluids, whether in the form of vapors, gases, or liquids. For simplicity of description I will presume that it is to be employed as a steam-superheater, and from this description 25 its general application will also be understood.

I will describe my invention with reference to the accompanying drawings, Figures 1 and 2 of which are sectional elevations at right 30 angles to each other, showing part of the spaces in the setting of the boiler with which the superheater is used, the said superheater-spaces being in communication with the flues 35 conducting the hot gases from the furnace or furnaces to the chimney and being provided or not with means for cutting off the said spaces from the flues when desired.

The outer tubes *a* have their lower ends closed, and their upper ends are expanded or 40 screwed or otherwise secured in the lower plate *b* of an outer box, preferably made of two dished plates *b* and *b'*, with abutting flanges bolted together. In this outer box is supported a smaller box *c* of such a size as to leave 45 all round it a space for steam between it and

the outer box. The body of this inner and smaller box can be conveniently made of rectangular pipe form, as shown in Fig. 2, and in longitudinal halves, with removable end pieces *c'*, the whole being connected by studs 55 and nuts *d* *d'*, as shown. The said end pieces *c'* or the bolts *d* *d'* (or both) and also other bolts or feet at intervals, if desired, can be used as rests to support the lower side of the said inner and smaller box *c* at the requisite 60 distance from the lower plate *b* of the outer box. The upper ends of the inner tubes *e* are expanded or screwed or otherwise secured in the lower side of the inner and smaller box *c*. A transverse division *f* across the inside of 65 the outer box divides the space between it and the inner and smaller box *c* into two compartments *b'* *b*. Connections with openings in the upper plate of the outer box are made at *g* with the source of steam-supply to be superheated and at *h* with the place to which the superheated steam is to be supplied, the opening *g* communicating with the compartment *b'* and the opening *h* communicating with the other compartment, *b*. 70

The steam to be superheated passes into the compartment *b'* above the inner and smaller box *c* and passes to beneath the said box *c* and down the set of outer tubes *a* communicating with this compartment *b'*, and then the 75 said steam passes up the inner tubes *e* of the said set and into the inner and smaller box *c*, along which the said steam passes and descends the inner tubes *e* of the other set of tubes, and then the said steam passes up the 80 outer tubes *a* of this set into the second compartment *b* of the outer box, from whence it passes to the place of utilization.

i is a casting (on the setting around the spaces for the superheater) by which the superheater is suspended in the said spaces by 85 the outer box resting on the said casting.

j shows the attachment for the safety-valve.

By constructing apparatus as described it can be readily taken apart for cleaning or 90 repairs.

Having now particularly described and ascertained the nature of my said invention and in what manner the same is to be performed, I declare that what I claim is— 95

1. In superheaters, or apparatus for effecting interchange of temperature, the combination of an outer and an inner box relatively arranged so that a space surrounds the inner box, means for separating the said space into two compartments, an inlet communicating with one compartment and an outlet communicating with the other compartment and sets of Field tubes having the outer members of 5 one set communicating with one of the said compartments and the outer members of another set communicating with the other of the said compartments, the inner members of the said Field tubes all communicating with 10 the inner box.

2. In superheaters, or apparatus for effecting interchange of temperature, the combination of an outer box made of dished flanged plates bolted together and an inner box arranged inside the outer box so that a space surrounds the inner box, a division separating the said space into two compartments, an inlet communicating with one compartment and an outlet communicating with the other 20 compartment, and sets of Field tubes having the outer members of one set communicating with one of the said compartments and the outer members of another set communicating with the other of the said compartments, the inner members of the said Field tubes all communicating with 25 the inner box.

with the other of the said compartments, the inner members of the said Field tubes all communicating with the inner box. 30

3. In superheaters, or apparatus for effecting interchange of temperature, the combination of an outer box made of dished flanged plates bolted together and an inner box made of longitudinal parts and end pieces secured by bolts and nuts and arranged inside the outer box so that a space surrounds the inner box, a division separating the said space into two compartments, an inlet communicating with one compartment and an outlet communicating with the other compartment and sets of Field tubes having the outer members of one set communicating with one of the said compartments and the outer members of another set communicating with the other of the said compartments, the inner members of the said Field tubes all communicating with 40 the inner box. 45

In testimony whereof I have signed my name 50 to this specification in the presence of two subscribing witnesses.

JÖRGEN BJÖRNSTAD.
